APPARATUS FOR PRODUCING MOLDED
PULP ARTICLES

Carl Stack, Gary, Ind.

Application July 24, 1937, Serial No. 155,383

2 Claims. (Cl. 92—59)

This invention relates to improvements in apparatus for producing molded pulp articles and it consists of the matters hereinafter described and more particularly pointed out in the appended claims. The apparatus of the present invention contemplates the production of such molded pulp articles as pie plates, cake circles, food trays and the like but may be employed in making other articles, as will be apparent.

10 One of the objects of the present invention is to provide an apparatus of this kind which is simple in construction and is positive, fast and efficient in operation.

Another object of the invention is to provide 15 apparatus of this kind, wherein the molding dies rotate in a horizontal path about a vertical axis, so that the apparatus may be made relatively low in height for easy inspection and servicing when so necessary.

20 Again, it is an object of the invention to provide apparatus of this kind wherein the articles leave the same with a sharp clean edge due to the fact that all of the periphery of the pick up mold is entered into the pulp material and is withdrawn therefrom at the same time so that there is no back wash of material as occurs in the horizontal drum type of apparatus for a similar purpose.

The above mentioned objects of the invention, 30 as well as others, together with the many advantages thereof will more fully appear as the specification proceeds.

In the drawings:

Fig. 1 is a top plan view of an apparatus for 35 making molded pulp articles embodying the preferred form of the invention.

Fig. 2 is a transverse vertical sectional view through the same as taken on the line 2—2 of Fig. 1.

40 Fig. 3 is a detail transverse vertical sectional view on an enlarged scale through one of the mold or die supports of the apparatus and associated parts, the plane of the section being taken on the line 3—3 of Fig. 1.

Fig. 4 is a perspective view of one of the articles 45 produced by the apparatus.

Fig. 5 is a vertical detail sectional view through one of the mold or die supports and associated parts on a further enlarged scale and illustrates 50 a modified form of the invention which will be more fully described later.

Fig. 6 is a perspective view on a reduced scale of a certain cam track providing member embodied in the apparatus and which will be more fully referred to later.

55 Referring now in detail to that embodiment

of the invention illustrated in Figs. 1 to 3 inclusive of the accompanying drawings: 10 indicates as a whole the horizontally disposed base of the machine adapted for engagement upon any suitable kind of support. 11 indicates an upright stud or shaft fixed at its bottom end to the central portion of said base. As shown herein the bottom end of said stud or shaft carries a flange 12 bolted to the base as at 13. Sleeve 14 surrounds the stud or shaft 11 for rotation about the axis thereof, an antifriction thrust bearing 15 being interposed between the bottom end of said sleeve 14 and the flange 12. About midway between the ends of said sleeve is an outwardly extending radial flange 16.

15 17 indicates the horizontal table of the apparatus, disposed a suitable distance above the base and surrounding that portion of the sleeve 14 above the flange 16. Said table, which is in the form of a circular plate, rests upon and is secured to the flange 16 as by means of bolts 16a. A bevelled rack 18 is secured to the underside 20 of the table near its periphery. A bevelled driving pinion 19 on a shaft 20 meshes with the rack to drive the table continuously in one direction about the axis of the stud or shaft.

Vertical posts or pins 21 are adjustably secured at their bottom ends in the base plate, in arcuately spaced relation on the same circle. The top end of each post or pin is guidingly engaged 30 in an associated recess 22 in the underside of a ring 23, the top surface of which has a faced fit against the associated part of the underside of the table. Annular inner and outer packing rings 24 are disposed in coacting grooves in the 35 ring 23 and in the table respectively to provide a running seal between the two.

The posts 21 each support a shoulder or washer 25 and a helical expansion spring 26 surrounds each post between said shoulder and the ring 23. 40 These springs operate jointly to yieldingly hold the said ring in snug engagement with the underside of the table. A nut 27 is threaded on each post 21 to engage the shoulder or washer 25 thereon and by which the tension of each spring 45 may be accurately gauged. A second nut 28 is threaded on each post and whereby the respective posts may be adjusted in height relatively to the base.

50 In the upper surface of the ring 23 is formed an incomplete circular groove 29 as best appears in dotted lines in Fig. 1, the ends of the groove being spaced apart by a blank portion 30 of the ring 23. A suction pipe 31 (see Fig. 1) is connected at one end to the groove 29 in said ring, and is connected at its other end to a suction pump 55

(not shown). A pipe 32 (see Fig. 1) for air under pressure, opens upwardly through the blank portion 30 of the ring 23, radially outward from the circle of the groove 29, as indicated at 33.

- 5 The table 17 carries a plurality of arcuately spaced, upright guide posts 34 arranged on a circle, outside that of the ring 23. Each post carries clamp nut 35 for securing it in position with respect to the table. 36—36 indicate a plurality of mold or die supports, one for each post 34 and each including a downwardly facing hollow head 37. Each mold support has associated therewith a vertically depending actuator rod 38. The top end of each actuator rod extends through 10 its mold support and clamp nuts 39 are operatively threaded on the rod to clamp against the top and bottom surface of the mold support. Each actuator rod has sliding guided bearing in a sleeve 40 provided therefor in the table. The bottom end of each actuator rod is bifurcated to receive a roller 41.

On the base 10 of the apparatus, in the circle of the actuator rods 38 is an incomplete circular cam track 42 shown in perspective in Fig. 6. 25 The rollers 41 of all of said actuator rods are adapted to ride around the cam track 42. It is apparent that in the rotation of the table, the mold supports 36 rotate therewith, and due to the engagement of the rollers 41 with the cam track, will move vertically with a rising and falling action in accordance with the contour of said track.

As shown herein, the hollow head of each mold support carries a perforated forming mold or die 43 covered by a foraminous sheet such as a piece of fine mesh screen 44. On the table 17 axially in line with each forming mold or die is a perforated compression die 45, each seated in a recess 46 in the table. As herein shown, there is only one mold or die associated with each support but in practice, it is contemplated that a plurality of such molds or dies will be carried by each support, say conveniently four thereof. Under such conditions, there will be four coacting compression dies 45 aligned with each four forming molds or dies 43.

To insure accurate registration between each compression die and its associated and forming mold or die in the relative movement of said dies toward each other, a plurality of upright pilot pins 47 are associated with each compression die. As shown herein, the pilot pins are secured in the table about the compression dies. The hollow head 37 of each die support is formed with openings 48 for registration with the pilot pins so that in the relative axial movement between the die support and the table, the pins enter said openings. Thus an accurate registration of each forming mold or die with an associated compression die is afforded.

A pair of flexible tubes 50 and 51 respectively, is associated with each forming mold or die, the former being the suction tube and the latter being the pressure tube. One end of the suction tube is suitably connected to the hollow head of the associated support, while the other end of said tube is connected to a nipple 50a secured to the table in the circle of the suction groove 29. One end of the pressure tube is suitably connected to the hollow head of the associated support while the other end of the tube is connected to a nipple 51a secured in the table in the circle of the air pressure inlet 33.

The table, when viewed in plan as in Fig. 1, 75 rotates clockwise. Above and overhanging a

part of the table, to one side of the radial plane passing through the air pressure inlet 33, is an open top arcuate tank 52 to hold a supply of watery pulp material. This tank, which is rigid with the base 10, is supported by posts 52a rising from said base. These posts support the tank at such an elevation above the table that the compression dies 45 and associated pilot pins 47 may pass beneath the tank in the rotation of the table. The tank has a pulp material inlet 53 and a pulp material outlet 54, the inlet and outlet leading from and to a main source of supply and constituting a part of a pulp material circulating system, whereby the pulp material in the tank is caused to flow in the direction of the 15 rotation of the table.

55 indicates a take off conveyor arranged in the radial plane of the air pressure inlet 33 before mentioned, in such a manner as to be disposed between the table 17 and the supports 36 20 when the latter are in their highest elevation above the table. When the supports 36 move into said radial plane, the molded pulp article is discharged from the forming mold or die thereof onto the conveyor to be carried thereby 25 through suitable drying means not shown herein. The forming dies 43 and the compression dies 45 as shown herein are of such formation as to produce a conventional molded pulp pie plate, one of which appears in Fig. 4.

30 The shape and contour of the cam track 42 best appears in Fig. 6. As shown therein, the ends 42a—42b are spaced apart and slope upwardly in opposite directions from the lowest to the highest parts of the cam. Associated with 35 the end 42b of the cam is a depressed portion 42c and which controls the projection and the retraction of the forming molds or dies into and out of said tank.

Assume that in the operation of the apparatus 40 wherein the table 17 and die supports 36 are rotating clockwise, one of the die supports 36 is swinging into and through the radial plane of the air pressure inlet 33 before mentioned, at which time it is in a position above the conveyor 55. 45 When said support 36 is disposed in said plane, the nipple 51a associated with the air pressure tube 51 thereof, lines up with the air pressure inlet 33 in the ring 23 at which time the suction tube nipple is cut off from the suction groove 29. 50 At this time, air under pressure passes through the tube 51 into the head 37, to blow through the forming die and associated screen thereof, to discharge a formed but undried pulp article upon the conveyor 55 for delivery to the drying means 55 before mentioned. At this time the support is riding at such an elevation on the cam track as to bring its die and screen above the plane of the top edge of the tank.

In the further rotation of the table and the 60 die support, the roller 41 of the actuator rod 40 associated with said die support is riding upon the high side of the cam track but is approaching the cam track depression 42c, this occurring about the time the die support has passed over 65 the conveyor and is approaching the inlet end of the tank 52.

So soon as the die support clears the inlet end 70 wall of the tank, the roller 41 of its actuator rod, enters the cam track depression 42c. Due to gravitational action of the head, the hollow head of the support descends to dip and submerge its forming mold or die into the pulp material in the tank. At this time the inlet nipple 50a of the associated suction tube 50 registers with the suc- 75

tion groove 29 in the ring 23 so that a suction action develops in the hollow head 37 of the mold support to suck up a quantity of the pulp which is retained on the screen carried by said support. By reason of circulating the pulp material through the tank in the direction, as before described, no splashing or undue turbulence is present as the forming mold or die enters the tank. As the forming mold or die approaches the discharge end of the tank, the roller 41 of its associated actuating rod 38 rides up the other side of the depression 42c onto a high spot of the cam track adjacent the cam track end 42b. At this time the mold or die with its charge of pulp fibres upon its screen will have cleared the discharge end of the tank.

As said roller travels down said end 42b of the cam track, it is apparent that through the actuator rod 38, the mold support descends so that the forming mold or die descends therewith to meet the associated compression die 45, the pilot pins 47 and holes 48 assuring registration between said dies. When the two dies are engaged, the roller 41 is in a position between the ends of the cam track and is disposed a slight distance above and out of contact with the base 10. By reason of the weight of the die support and associated parts, the forming mold or die operates in conjunction with the compression die to impart a squeezing pressure upon the fibres disposed upon the screen of the forming mold or die to compress said fibres and form the article. This gives the article a better and smoother appearance and extracts as much of the water content from the formed article, as is possible.

As the roller 41 of the associated actuating rod engages and rides up the inclined end 42a of the cam track, the mold support rises in accordance with the inclination of said end, the partly formed article being held in place upon the forming mold or die by suction. This suction continues to extract water until the article is ready to be discharged onto the conveyor. When said die support reaches the position above the conveyor, before mentioned, the nipple 50a moves onto the blank space between the ends of the groove 29 in the ring 23 and the nipple 51a registers with the air pressure inlet 33 so that a blast of air is discharged through the hollow head of the mold support to loosen the formed article for depositing the same upon the conveyor for discharge.

It is apparent that the operation of the die members occurs in succession so that the apparatus is continuous in its operation of producing articles.

In Fig. 5 is illustrated a slightly modified form of construction directly associated with the forming mold or die to provide a pressure for urging the same into a more intimate contact with its associated compression die. Such a construction which is located in a radial plane between the ends 42a—42b of the cam track, comprises an upright bracket 60 secured to the base 10, outside the periphery of the table. Said bracket has a laterally extending arm 61 at the top that is disposed in a plane above the top of the die supports as they pass beneath the same so as to overhang a portion thereof. Slidably in said arm in the circle of the axis of the dies, as they pass beneath said arm, is a spring pressed plunger 62. The bottom end of this plunger is bifurcated to receive a roller 63 which engages with a top portion of the support 36 as the same passes under the same. The opposite sides of the sup-

port have laterally extending inclined surface portions 64 upon which the roller rides as the support passes under the same. As the roller rolls up the advancing surface portion 64, this compresses the spring, which imparts its pressure to the support to force the forming mold or die on said support into intimate compression engagement with the compression die. As the support passes beneath the roller, the roller moves downward upon a trailing surface portion on the opposite side of the support and off the same to release the pressure from the support. This action is repeated each time a support passes beneath the roller.

The apparatus is simple in construction and is positive and fast in operation.

While in describing the invention, I have referred in detail to the form, arrangement and construction of the parts involved, the same is to be considered only in the illustrative sense so that I do not wish to be limited thereto except as may be specifically set forth in the appended claims.

I claim as my invention:

1. Apparatus for producing molded paper pulp articles, means providing a support, means providing a horizontal member rotatably mounted on said support, a plurality of compression dies rigidly mounted on the upper surface of said rotatable member, a plurality of forming dies arranged above said rotatable member, each of the last mentioned dies including a die carrying head and a lateral extension, a plurality of upright guide posts on said rotatable member, one for each forming die and each passing through the lateral extension thereof and having a sliding engagement therewith, an actuator rod fixed to each forming die and having a sliding bearing engagement through the rotatable member, said actuator rod supporting the forming die, anti-friction means on the lower end of the actuator rod, and an incomplete cam mounted on the support beneath the rotatable member and adapted to be traversed by the anti-friction means on the lower end of the actuator rod, whereby the forming die is adapted to fall by gravity into engagement with the compression die to compress the article therein.

2. Apparatus for producing molded paper pulp articles, means providing a support, means providing a horizontal member rotatably mounted on said support, a plurality of compression dies rigidly mounted on the upper surface of said rotatable member, a plurality of forming dies arranged above said rotatable member, each of the last mentioned dies including a die carrying head and a lateral extension, a plurality of upright guide posts on said rotatable member, one for each forming die and each passing through the lateral extension thereof and having a sliding engagement therewith, an actuator rod fixed to each forming die and having a sliding bearing engagement through the rotatable member, said actuator rod supporting the forming die, anti-friction means on the lower end of the actuator rod, an incomplete cam mounted on the support beneath the rotatable member and adapted to be traversed by the anti-friction means on the lower end of the actuator rod, whereby the forming die is adapted to fall by gravity into engagement with the compression die to compress the article therein, and means engaging the head for imparting additional pressure on the forming die.
